UNITED STATES PATENT OFFICE.

GEORGE W. PIGGOTT, OF NEW YORK, N. Y., ASSIGNOR TO HARTFORD CARPET COMPANY, OF HARTFORD, CONNECTICUT.

DESIGN FOR CARPET.

SPECIFICATION forming part of Design No. 11,867, dated July 13, 1880.

Application filed February 12, 1880. Term of patent 3½ years.

To all whom it may concern:

Be it known that I, GEORGE W. PIGGOTT, of the city, county, and State of New York, have invented a new and original Design for 5 a Carpet, of which the following is a specification.

This invention relates to a new and original design for carpets, oil-cloths, and similar fabrics.

10 It consists in the novel grouping and configuration of figures, hereinafter more fully described and claimed.

The accompanying photograph illustrates a face view of a carpet having my new design.

15 A is a rectangular figure of peculiar outline, having wings P and R.

B is an L-shaped figure, separated from A by borders a and b. These figures are ornamented with flowers and leaves on their 20 ground, those in figure A extending over the border a to figure B.

C is a similarly-shaped figure, with borders d d' and flowers and leaves on its ground. The flowers and leaves from figure B extend 25 over into figure C.

E is a square figure with borders e e' and flowers on its ground, and with border f.

F G H I are a group of rectangular figures lapped together. Figure F has a border, g, 30 and on its ground are small flowers and leaves. Figure G has borders g' g² and flowers, stems, and leaves on its ground. Figure H has borders h h' and a brilliant group of flowers, i, which connect it with surrounding 35 figures. Figure I has borders j l m n and a group of stems, leaves, and flowers, which connect it with a rectangular figure, J, which has a border, o, and rose-buds and leaves on its ground.

40 K is a rectangular figure, partly overlapped on one corner by a smaller rectangular figure L. Figure K has a border, p, and figure L has borders q q'.

M is the L-shaped upper part, and N the L-shaped lower part, of an irregular figure. 45 The part M contains a brilliant group, r, of flowers on its ground, which extend over its borders into figures H L. The part N contains flowers on its ground, which extend over 50 into the figure K and into the part M of the figure M N.

O is an L-shaped figure with stems ornamented with leaves and flowers on its ground.

I claim—

1. The design for a carpet, consisting of the 55 figures A B, borders a b, and connecting vines and flowers, substantially as shown.

2. The design for a carpet, consisting of the figure B, figure C, borders d d', and connecting vines and flowers, substantially as shown. 60

3. The design for a carpet, consisting of the figure E and borders e e' f, substantially as shown.

4. The design for a carpet, consisting of the figures F and G and borders g g' g², substantially as herein shown and described. 65

5. The design for a carpet, consisting of the figure H and borders h h', substantially as shown.

6. The design for a carpet, consisting of the 70 figure I, borders j l m, and the group i of stems, leaves, flowers, and vines, substantially as shown.

7. The design for a carpet, consisting of the group of figures F G H I, borders g g' g² h h' j 75 l m, and connecting vines, stems, and flowers, substantially as shown.

8. The design for a carpet, consisting of the figure K and border p, substantially as shown. 80

9. The design for a carpet, consisting of the figures K L and borders p n q q', substantially as shown.

10. The design for a carpet, consisting of the figure J and border o, substantially as shown. 85

11. The design for a carpet, consisting of the figures J I, borders o j m, and connecting vines and flowers, substantially as shown.

12. The design for a carpet, consisting of the figure M N and floral group r, substantially as 90 herein shown and described.

13. The design for a carpet, consisting of the figures M N and K, and connecting flowers and leaves, substantially as herein shown and described. 95

14. The design for a carpet, consisting of the figure O, substantially as shown.

15. The design for a carpet, consisting of the figures A B C E F G H I J K L M N O and the borders and vines and flowers, substantially as herein shown and described. 100

GEORGE W. PIGGOTT.
